194,794

TRANSPARENT COVER FOR SAUCEPAN OR OTHER KITCHEN UTENSIL

Paul F. Rahr, Manitowoc, Wis., assignor to Aluminum
Specialty Company, Manitowoc, Wis.

Filed Feb. 16, 1962, Ser. No. 68,863

Term of patent 14 years

(Cl. 44—1)

FIG. 1

FIG. 2

FIG. 3

FIGURE 1 is a top plan view of a transparent cover for saucepan or other kitchen utensil embodying my new design;

FIGURE 2 is a side elevational view thereof; and

FIGURE 3 is a fragmentary sectional view taken substantially on the line 3—3 of FIGURE 1.

The dominant features of the design are shown in full lines on the drawing.

I claim:

The ornamental design for a transparent cover for saucepan or other kitchen utensil substantially as shown.

References Cited in the file of this patent

UNITED STATES PATENTS

D. 172,839	Olswang	Aug. 17, 1954
D. 181,798	Krause	Dec. 24, 1957
2,281,649	Williams	May 5, 1942